TUFTING BUTTONHOLDER

Irving Sable and Aniceto R. Visitacion, New York,
N. Y., assignors to Unique Headboard Company,
Inc., Irvington, N. J., a corporation of New
Jersey

Application March 23, 1951, Serial No. 217,106

1 Claim. (Cl. 45—138)

1 This invention relates to a tufting machine and to improved tufting button holders used therewith.

The principal object of this invention is the provision of a tufting machine in which individually removable button holders are provided so as to facilitate and expedite the several operations involved in tufting textile materials, plastic sheeting, leather, artificial leather and the like. The advantages of removable button holders are more apparent in the closing stages of the tufting operation but they provide other advantages which relate to the adaptability of the machine to accommodate tufting buttons of widely varying dimensions.

More specifically, removable tufting button holders may be made in many different sizes so as to accommodate tufting buttons of every possible size. These tufting button holders are interchangeable, one with the other, irrespective of the dimensions or capacity of their button-gripping or button-clamping members. In all cases the shank portions of these button holders are identical in size and shape so as to fit into holes of identical size and shape.

Another principal object of the invention is the provision of removable and interchangeable tufting button holders for tufting machines. These button holders are provided with square shanks so that they may be placed in any fixed position relative to the bed which supports them and the station of the operator of the machine. The button holders herein described and claimed are, in effect, collets which adjustably clamp the tufting buttons in place. Two forms of tufting button holders are shown and described in the present application. Both involve the use of split or bifurcated clamping means which may be compressed or squeezed together to grip the head of the tufting button. In one case, the bifurcated clamping member is squeezed together by means of a screw which extends transversely thereof. In the second case, the bifurcated clamping member is squeezed together by means of an internally threaded collar or nut which rotates on an axis that coincides with the longitudinal axis of said bifurcated clamping member. Said bifurcated clamping member is tapered on the outside and the internally threaded collar engages said taper to cam the bifurcated clamping member into compressed or clamping position.

Another important object of this invention is the provision of an improved tufting button holder which is not removable from the bed or board which supports it. Instead, it is linked up with a locking and releasing mechanism which locks it into clamped position or releases it from

2 clamped position. More particularly, a considerable number of such non-removable button holders are linked up to a single locking and releasing means so that in one operation the entire group of button holders may be locked into clamping position or released therefrom. The principal advantage of this arrangement is the ease and speed by which a plurality of button holders may be actuated. This is to be distinguished from the principal advantage of the removable button holders which arises from the fact that at the conclusion of the tufting operation they may be lifted off their supporting bed or board, together with the tufted material itself. The tufted material may then be turned upside down and the button holders individually released from the tufting buttons.

Preferred forms of this invention are shown in the accompanying drawing, in which:

20 Fig. 1 is a front view of a tufting machine made in accordance with one form of this invention and using one type of tufting button holder herein claimed.

25 Fig. 2 is a view looking upwardly in the direction of arrows 2, 2 of Fig. 1, showing the compressing board or ram which compresses the filler of the material being tufted.

Fig. 3 is a view looking downwardly in the direction of arrows 3, 3 of Fig. 1, showing the tufting board.

30 Fig. 4 is a fragmentary section through the compressing board or ram.

Fig. 5 is an enlarged, fragmentary section showing the initial step in the tufting operation, to wit, the step of inserting the tufting buttons through the tufting material and supporting said tufting material on the tufting button holders.

35 Fig. 6 is a similar view showing the next step, namely, placing the button protectors and tufting material pleaters upon the button holders.

Fig. 7 is still another similar view showing the filling material in place on the tufting material.

Fig. 8 is still another similar view showing the backing material in place on the filling material and also showing the button protectors removed from the button holders.

Fig. 9 shows the ram in engagement with the backing material and compressing the filling material to the desired or predetermined extent, and also showing how the ends of one of the tufting buttons are bent over in fastening position.

Fig. 10 is a fragmentary face view of the tufted material.

45 Fig. 11 is a sectional view on the line 11—11 of Fig. 6.

Fig. 12 is a fragmentary view looking down-

wardly in the direction of arrows 12, 12 of Fig. 9.

Fig. 13 is a side view of one of the tufting button protectors and tufting material pleaters used in the present tufting machine.

Fig. 14 is another side view thereof looking from a vantage point which is 90° removed from the vantage point of the view in Fig. 13.

Fig. 15 is a side view of one form of tufting button holder.

Fig. 16 is a bottom view thereof.

Fig. 17 is another side view thereof which is 90° removed from the view of Fig. 15.

Fig. 18 is another view of the same button holder, showing it partly in section to expose the screw clamping means and the button seat which receives and supports the head of the button.

Fig. 19 is a side view of a tufting button holder made in accordance with another form of this invention.

Fig. 20 is a bottom view thereof.

Fig. 21 is a vertical section through said second form of button holder, showing the button clamping means, including the seat which receives and supports the button head.

Fig. 22 is a fragmentary view, partly in vertical section, showing another form of tufting button holder, namely the form illustrated in Fig. 1, and also showing the clamping and unclamping means by which a plurality of such buttons may be clamped or unclamped simultaneously by means of a single control lever.

Referring now to the first four figures of the drawing, it will be seen that the tufting machine which is herein claimed comprises a frame 10 which supports a tufting board 12, a plurality of tufting button holders 14 mounted on said tufting board, and a compressing board or ram 16. This ram is connected by means of a spider 18 to a hydraulic press 20 or the like by which it is moved into and out of operative position with respect to the material being tufted. The tufting machine frame 10 includes four corner posts 22 and it will be noted in Fig. 2 that compressing board 16 is cut out at its four corners to accommodate said four corner posts which then serve as guide posts to guide the vertical movements of said compressing board. To facilitate these vertical movements, counter-weights 24 and 26 are provided to counter-balance the weight of said compressing board. These weights are connected to the compressing board by means of cables 28 and 30, respectively, and it will be noted that pulleys 32 and 34 on frame 10 support cable 28 and corresponding pulleys 36 and 38 support cable 30.

The tufting button holders 14 are uniformly spaced from each other on tufting board 12 as Fig. 3 clearly shows. It is necessary to provide holes 40 in the compressing board to accommodate the tufting buttons which said button holders support. See Fig. 4. It is also necessary to strengthen the compressing board in order to allow one press to operate it and to uniformly distribute the load. Consequently reinforcing ribs 42 are provided on said compressing board, and it will be noted in Fig. 4 that these ribs project upwardly from said board. Reinforcing ribs 42 criss-cross or intersect each other at right angles and square recesses 44 are thereby provided above holes 40. These square recesses are sufficiently large to accommodate the hands of the operators of the machine when the ends of the tufting buttons are being bent over.

Fig. 22 is an enlarged detailed view of one of the button holders 14 as well as of the control

mechanism for clamping and unclamping said button holders. It will there be seen that each button holder 14 comprises a tubular member 46 which is reduced at its lower end 48 to fit into a hole 50 in tufting board 12. Tubular member 46 has an outwardly tapered or flared inner wall at its upper end so as to provide an outwardly flared or enlarged opening at said upper end. Stated differently, the opening which extends through said tubular member is uniform throughout except at the top where it is enlarged. Slidably mounted in said tubular member is a rod 52 which is bifurcated at its upper end. More specifically, there is a split 54 in the top end of said rod extending downwardly and longitudinally thereof. The split ends at its lower end in an enlarged opening 56 in order to weaken the walls and provide for greater flexibility. The bifurcated end of rod 52 tapers outwardly to increased cross-sectional dimensions to correspond to the taper of the hole in tubular member 46. At the top of the bifurcated end is a seat 58 which extends across slit 54 and which is adapted to accommodate the head 60 of tufting button 52. When rod 52 is pulled downwardly, its tapered, bifurcated end becomes compressed under the camming action of the tapered end of tubular member 46 and the head of the button is thereby gripped and clamped in its said seat.

The lower end of rod 52 is fastened to a board 64 by means of nuts 66 and 68, respectively. It will be noted that the lower end of said rod is provided with screw threads to accommodate said nuts. Paralleling rod 52 is another rod 70 which is fixed at its upper end to tufting board 12 by means of flanged collar 72 and pin 74 which fixes said rod to said collar. A cam 76 having a flange 78 is mounted on rod 70 and fixed to board 64 by means of bolts 80 and 82, respectively. There is a slide fit between rod 70 and cam 76 so that the cam is free to move either upwardly or downwardly on said rod. At the lower end of rod 70 is a handle 84 which has a pin 86 projecting into an annular groove 88 formed in said rod 70. The handle is free to rotate on said rod but it is locked against vertical movement relative thereto. The handle is provided with a second pin 90 which projects into a cam groove 92 formed in said cam 76. When the handle is turned in one direction, it causes cam 76 to move upwardly on rod 70 and when it is turned in the opposite direction, it causes said cam to move downwardly on said rod. Since the cam is fixed to board 64 and since a plurality of rods 52 are also fixed to said board, the effect of moving the handle is to cause said board and said rods to move either upwardly or downwardly and thereby to open or close the clamping means at the top of each rod. It will be noted in Fig. 1 that board 64 is only one of three similar boards, the other two being identified as boards 64a and 64b, respectively.

In Figs. 15 to 18 inclusive, a tufting button holder 94 is shown which may be removably mounted in a tufting board corresponding to tufting board 12. Button holder 94 comprises a bifurcated clamping member 96 having a button seat 98 at its upper end, and a square shank 100 which extends downwardly from said bifurcated clamping member. Said bifurcated clamping member has a slit 102 which corresponds to slit 54 above mentioned, and which terminates at its lower end in a transverse opening 104, corresponding to opening 56 above mentioned. A screw 106 is provided in the bifurcated member,

transversely thereof, and it is in screw-threaded engagement with one of the segments of said bifurcated member. The opposite end of the screw is headed over and provided with an actuating arm 108. When the screw is turned in one direction by means of said handle, it tends to pull or squeeze the bifurcated member together and thereby to clamp the head in place, and when the screw is turned in the opposite direction by means of the same handle, it tends to release the bifurcated member to the extent of allowing it to spring back to its pre-clamping position, thereby releasing the button.

Shank 100 is square and the hole in the tufting board which receives it is correspondingly square. Hence the button holder will be unable to turn or otherwise change its position relative to the tufting board once it is inserted therein. It will thus be possible to insert a plurality of such button holders into a common tufting board with all of their operating handles occupying similar relative positions so as to facilitate their manipulation. Similarly, the bifurcated portion of each button holder is also square in cross-sectional shape. See Fig. 16. There is a good reason for this, as will clearly appear from Figs. 6 and 10. In the operation of the present device, a plurality of button holders 94 are mounted on a common tufting board 110. A plurality of tufting buttons 62 are then inserted into said button holders and clamped in place therein. The tufting material 112 is then mounted on said buttons in the following manner: It will be seen in Fig. 11 that the tufting material has a plurality of button receiving holes 114 formed therein and reinforcing members 116 affixed thereto in the area surrounding said holes. The holes are formed in predetermined spaced relationship, being farther apart from each other than the buttons are from one another. The tufting material is then mounted on the buttons by simply slipping the bifurcated shanks of the buttons into said preformed holes and the tufting material is then brought downwardly until it rests upon the button holders. Since the holes in said tufting material are spaced farther apart from each other than the buttons are spaced from one another, said tufting material will tend to sag in the spaces between the buttons as Fig. 5 clearly shows. It is at this time that tufting button protectors 118 are placed over the tufting buttons and secured to the button holders.

Each button protector comprises a pair of pivotally connected members 120 and 122, respectively. The upper ends of the two members are bent inwardly toward each other so as to engage each other at their very top ends. Member 120 is provided at its top end with a pair of spaced lugs 124 which receive the top end of member 122 between them and prevent disengagement between the top ends of the two members. The bends in said members 120 and 122 are situated intermediate rivets 126 which constitute the pivotal connection between said members, and the top ends thereof. Hence, the two members 120 and 122 are maintained under constant tension which tends to push their lower ends toward each other. Each of the two members 120 and 122 is provided at its lower end with a pair of spaced, 70 downwardly extending legs 128 having outwardly extending feet 130 formed at the bottom thereof. When the button protector is placed over the button, its four legs 128 engage the four flat sides of the button holder and the four spaces between 75

said legs receive the four corners of said button holder. Consequently, the position of the button protector may be controlled by controlling the position of the button holder.

5 When the button protector is placed over the button following the operation of mounting the tufting material thereon, the slits between the legs of the button protector tend to pleat the tufting material and to form the pleats 132 which are shown in Fig. 10. Since the relative positions of the button holders and the button protectors are always predetermined and under control, the lines on which pleats 132 are formed will also be predetermined and the pleats will always intersect each other at right angles. The next step in the tufting operation is to place the cotton filler or batting 134 on the tufting material and the step after that is to place a layer 136 of palm fiber or hair on the cotton batting. The button protectors are then removed and a backing material 138 is then placed upon layer 136, the pointed ends of the buttons projecting through said backing material. See Fig. 8. The next step is to bring compressing board 16 down upon 15 the backing material to compress the two layers of filling material. The ends of the buttons will project through holes 40 in said compressing board as Fig. 9 clearly shows. Retaining rings 140 are then slipped over the upwardly projecting ends of the buttons and said upwardly projecting ends are then bent over in conventional manner as Figs. 9 and 12 clearly show. The compressing board is then lifted away from the tufted material and the tufting operation is complete. 20 25 30 35 40 45 50 55 60 65

All that remains to be done is to remove the button holders from the buttons and this can be done by simply lifting the tufted material, together with said button holders, off the tufting board and then turning it upside down so that the button holders project upwardly. The button holders may then be individually unclamped from the buttons and reinserted into the tufting board for the next tufting operation.

The modification shown in Figs. 19, 20 and 21 differs from the button holder last above described only in the means for compressing its bifurcated end. More specifically, button holder 142 has a square shank 144 which projects downwardly, an intermediate portion 146 which is provided with external screw threads, and an upper bifurcated portion 148. The bifurcated portion 148 flares outwardly and upwardly and its slit 150 extends longitudinally thereof and terminates at its lower end in a transverse opening 152. A seat 154 is formed in the top end of said bifurcated portion to receive the head of a tufting button and said seat extends across said slit 150. A collar 156 which is internally threaded at its lower end is mounted on the threaded intermediate portion 146 and it projects upwardly into engagement with the outwardly flared sides of the bifurcated portion 148. When the collar 156 is turned in one direction, it moves downwardly on threaded intermediate portion 146 and tends to release the bifurcated upper portion. When said collar is turned in the opposite direction it tends to move upwardly and to engage and squeeze the bifurcated portion together, thereby locking the head of the tufting button in seat 154. Button holder 142 is used in substantially the same manner as button holder 94 above described.

The foregoing is descriptive of preferred forms of this invention. These forms may be modified and other forms may be provided within the broad scope and coverage of the invention.

Having thus described our invention, what we claim as new and desire to secure by Letters Patent, is:

A tufting button holder comprising a vertically bifurcated body member, a button seat at the top of said bifurcated body member, a shank at the bottom of said bifurcated body member, a transverse screw in said bifurcated body member which positively clamps the same together, the screw being provided with a head and with an actuating arm connected to said head, said screw being in threaded engagement with one side of said bifurcated member, the head of said screw being in engagement with the other side of said bifurcated member, whereby turning said screw by means of said arm in one direction draws the two sides of the bifurcated member together, and

whereby turning said screw by means of said arm in the opposite direction releases the sides of said bifurcated member, said bifurcated body member and the shank being rectangular in cross section.
